UNITED STATES PATENT OFFICE.

RANDOLPH B. HANCOCK, OF GARY, INDIANA.

LOOPING AND GUIDING DEVICE FOR ROLLING MILLS.

Application filed August 9, 1923. Serial No. 656,548.

My invention relates to a looping and guiding device for rolling mills and has for one of its objects the provision of means placed between two roll stands for the purpose of guiding the strips of material passing from one roll stand to another and permitting loops to be formed in such strips of material during the rolling operation caused by different speeds of travel of the sets of rolls.

Another object of my invention is the provision of guiding means which performs primarily the function of guiding the strips of material from one roll stand to another but which releases the said strips during the actual rolling operation, so that they are free to form loops as they pass from one stand to another without gripping the thin strips of material or interfering in any way with the movement of the strips of metal after they are fed into the rolls.

Another object of my invention is the provision of a guiding means which is semi-automatic in its operation and which, while partially under control of an operator, automatically releases the strip of material as soon as the forward end of the material is fed into the pair of rolls, so that the possibility of buckling is reduced to a minimum and also the possibility of the material doubling back upon itself and being spoiled in the rolling operation is also reduced to a minimum.

Another and further object of my invention is the provision of a guiding member which operates with various widths of material within certain limitations, thereby avoiding the necessity for changing the guiding member each time a strip of different width is rolled, thus necessitating the stopping of the rolls and the loss of time while the change is being made, and also insures proper centering of the material between the rolls.

Another object of my invention is the provision of guiding means which are adjustable in both vertical and horizontal directions so that the strips of material are always properly fed into the rolls.

These and other objects of my invention will be more fully and better understood by reference to the accompanying sheets of drawings, and in which—

Figure 1 is a plan view of my improved invention;

Figure 2 is a rear elevational view of the device shown in Figure 1;

Figure 3 is a detail view in cross-section through the guiding member and cylinder;

Figure 4 is a detail plan view of the valve operating mechanism controlling the operation of the cylinder;

Figure 5 is a detail elevational view of the valve mechanism illustrated in Figure 4; and

Figure 6 is a cross-sectional view of a modified form of guiding bar.

Referring now specifically to the drawings, a foundation 10 is shown positioned between a pair of roll housings 11 on one side and 12 on the other, within which a pair of upper rolls 13 and 14 are shown with a pair of lower rolls 15 and 16, also being mounted therein. Upon the roll stand 11 is positioned a pair of brackets 17 and 18 within which is mounted a shaft 19. The roll stand 12 has a pair of brackets 20 and 21 secured thereto and which support a shaft 22 in exactly the same manner as the shaft 19, heretofore described, is supported. Adjustably positioned upon the shafts 19 and 22 and supported at each of its ends is a trough designated as a whole as 23 and composed of a stationary bar 24 of any cross-sectional area desired, but preferably rectangular in cross-section, as shown in the drawings, and a bar 25 U-shaped in cross-section and which abuts against the member 24 along one side thereof, forming a channel between the two roll stands 11 and 12, through which the material passes from one set of rolls to the other, the bar 25 having brackets 25^a and 25^b at each of its ends with bolts 25^c and 25^d extending into the bar 25, the said brackets having curved lower sides adapted to engage the shafts 19 and 22. Mounted upon the foundation 10 by means of a bed plate 26 is a cylinder 27 having a piston 28 located therein and having ports 29 and 30 at each of its ends through which a source of power, such as steam, compressed air or hydraulic pressure, can be admitted and exhausted, as will be more fully described hereinafter, the movement of the said piston 27 and its connections serving to move the bar 25 during the operation of the device as the material is rolled. Secured to the movable bar 25 is a pair of brackets 31 and 32 with a pair of inner brackets 33 and

34 secured thereto for additional support,

these two latter mentioned brackets also being secured to the bar 25. The brackets 31 and 32 are secured to a cross-head 35 mounted upon the piston 28 by means of a pin 36 so that as the piston is moved backward and forward the movable bar 25 is slid along the rods 19 and 22, thus opening and closing the channel formed between the two stands of rolls as the material is fed therethrough. At 10 the rear end of the bed plate 10 is an up-standing lug 37 having a bolt 38 in threaded engagement therewith, the said bolt having a lock nut 39 mounted thereon and forming an abutting member for the rear end of the 15 piston 28 and determining its rearward movement. At the forward end of the piston is positioned a smaller lug 40 integral with the said bed plate 26 and which has a bolt 41 mounted therein with a lock nut 42 secured thereto which forms adjusting means 20 for limiting the forward movement of the piston and securing the proper adjustment and feeding of the movable bar 25 against the stationary bar 24 and insuring proper 25 positioning of the guiding member with respect to proper centering of the work-piece between the sets of rolls. Connected to the port 30 at the rear end of the cylinder 27 is a pipe 43 leading to any source of steam 30 pressure, compressed air or hydraulic pressure supply and which is under the manual control of the operator of the device by suitable valve mechanism such as 68, such valve preferably being of the three-way type so 35 that the pressure may be exhausted.

From the foregoing description, the general operation of the device will be understood, particularly if it is desired to operate the device manually, but because of the 40 speed of travel of the material from one stand of rolls to another I have found it desirable to provide an automatic device for controlling the opening of the channel or guideway through which the material is fed from one roll stand to the other in order that the material may be properly fed into the set of rolls and allow for the looping of the material between the roll stands. To 45 perform this function I provide a pressure 50 operating mechanism and connections therefore to the movable bar 25 and a hinged bar 44 which projects upward through the bar 25 and is mounted upon a square trip shaft 45, the said member 44 having a downwardly projecting portion 46 to which a spring 47 is attached, the said spring being attached at its opposite end to the bracket 25^b and which serves the purpose of normally holding the member 44 upward in the 55 path of a bar which is fed through a channel in the guide 23. Mounted upon the bed 26 is a bracket 48 on the outer end of which is a second bracket 49 within which the squared trip shaft 45 is positioned and upon 60 which is secured a pawl 50. Secured to the 65 port 29 and the cylinder 27 is a pipe 51 having a three-way valve 52 positioned thereon upon which a disk 53 is mounted, the said valve having a supply pipe 54 connected thereto and leading to any suitable source of hydraulic pressure, steam or compressed air supply, and also having an exhaust pipe 55 leading therefrom through which the pressure is exhausted from the forward end of the cylinder 27 through the 70 port 29. The disk 53 has a pin 56 projecting upward therefrom and also has a slot 57 at one of its sides within which is mounted a pin 58 the outer end of which is secured to the bracket 48, the pin 58 75 acting as a stop as it engages the disk at one end or the other of the slot 57. On the lower side of the disk 57 and projecting downwardly therefrom is another pin 59 upon which a spring 60 is mounted and 80 which is anchored at its stationary end upon a pin 61 mounted within the bracket 48. Mounted upon the cross-head 35 is a catch 62 projecting outward and downward from the said cross-head 35 and in position to 85 engage the pin 56 extending upward from the disk 53 as the piston moves back and forth. A pin 63 projects upward from this catch and has a spring 64 positioned thereon which is anchored upon a second pin 90 65 mounted in the inner end of the bracket 32. The catch 62 is mounted in a recess 65^a in the cross-head 35 so that it has a pivotal movement about a bolt 66 upon which the catch is mounted and is held in abutting engagement with the rear side of the recess 65^a so that it is capable of being moved 95 relative to the cross-head in one direction only, that is, against the spring 64 so that this catch will operate the disk only when 100 the cylinder is moving backwards.

In Figure 6 is illustrated a modified form of guiding bar comprising a pair of members 69 and 70 each of which is U-shaped in cross-section and which are positioned in side to side engagement with each other in closed position forming a guiding channel 71 therethrough and which are operated by suitable separating means such as has been described heretofore and by means of which 110 one or two of the bars may be moved with relation to the other.

In operation it will be understood that as a strip of material leaves the rolls 13 and 15 and enters the guiding member 23 the two 115 members 25 and 24 have been brought together in closed position by the operator admitting pressure through the pipe 43 by means of a three-way valve 68 to the rear of the cylinder 27, so that the piston is left in its forward position, the valve 68 being thereupon reversed to exhaust and the valve 52 from the previous stage of operation being turned so that the pressure is exhausted from the forward end of the cyl- 120 125 130

inder 27. As soon as the forward end of the strip reaches the member 44 this member is turned down, rotating the trip shaft 45, which releases the pawl 50 from a projection 67 formed on the upper edge of the disk 53, whereupon the disk 53 is pulled around and closing the exhaust and opening the valve 52, so that pressure is admitted into the forward end of the cylinder 27 and overcoming the pressure in the rear of the cylinder, which may be exhausted by opening the valve 68, thereby pulling the movable bar 25 away from the bar 24 and opening the trough so that the material, which by this time has been fed forward into the second set of rolls, is thereupon released from the trough and allowed to feed freely from one set of rolls to the other and looping in any manner that may be desired owing to the difference in speed of travel of the set of rolls or for any other reason. As the piston 28 is forced back by the admission of pressure at the forward side thereof to the valve 52 the catch 62 engages the pin 56 and turns the valve back into the exhaust position, whereupon the pawl 50 engages the projection 67 on the disk 53 and holds the valve in exhaust or open position until such time as the sequence of operations described above takes place again.

It will be understood that as soon as the bar 25 is moved back the member 44 will be pulled from under the workpiece which is being rolled and this member will be pulled into position where it projects forward into the channel, bringing the pawl 50 downward where it will engage the projection 67 upon the disk 53.

The piston has an over-travel so that the disk is turned far enough so the pawl is sure to engage the projection 67 and upon the cylinder being returned the catch 62 passes by the pin 53 by reason of the spring 64 allowing the catch 62 to turn upon the pivot point 66. The piston is then allowed to remain in stationary position until the next strip of material is fed from the rolls, whereupon the same sequence of operation takes place as heretofore described.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. In combination a pair of roll stands, a guide extending between said roll stands, the guide comprising a pair of separable members one of said members having a channel therein and means controlled by the passage of the bar through the said channel whereby the member having the channel

therein is pulled away from the other member, the members being separable in a horizontal direction whereby clearance is allowed to a bar passing between the roll stands.

2. In combination with a pair of roll stands, a guide extending between said roll stands comprising a pair of separable members one of said members having a channel therein, means for moving the member having the channel therein, whereby the guide is opened and tripping means in said guide operated by the passage of the bar through the said guide whereby the said means for moving the said separable member is actuated, the members being separable in a horizontal direction whereby clearance is allowed to a bar passing between the roll stands.

3. In combination with a pair of roll stands, a guide extending between said roll stands, the said guide comprising a U-shaped member having a channel at one side thereof and a normally stationary second member, means for actuating said U-shaped member and tripping means controlled by the passage of the bar through said channel adapted to control the opening of the said channel, the U-shaped member being moved away from the stationary member in a horizontal direction and out of the path of a bar passing between the roll stands.

4. In combination, with a pair of roll stands, a guide member extending between said roll stands, supporting means for said guide member, the said guide comprising a pair of separable members one of said members having an open side recess therein, means whereby the member having the recess therein is moved toward and away from the other member comprising the guide, the member having the recess therein being moved away from the stationary member in a horizontal direction and out of the path of a bar of metal passing between the roll stand.

5. In combination with a pair of roll stands, a guide member comprising a stationary member and a movable guide member having a longitudinally extending channel therein, an operating cylinder, connections for said operating cylinder and said movable guide member and means for admitting an operating fluid to said cylinder and exhausting the same therefrom whereby the said movable guide member is moved toward and away from said stationary member in a horizontal direction.

6. In combination with a pair of roll stands, a guide member extending from one roll stand to the other, support members for said guide member, the said guide member being composed of a normally positioned stationary member and a movable member having a longitudinal extended channel

- therein adapted to be moved toward and away from said stationary member, an operating cylinder for said movable member, connections from said cylinder to said 5 movable member and an automatic tripping device for admitting pressure to said cylinder and moving said movable guide member away from said stationary member in a horizontal direction.
- 10 7. In combination with a pair of roll stands, support members mounted upon said roll stands, a longitudinally separable guide member positioned upon said support members and comprising a normally stationary member and a movable member having a channel therethrough, a cylinder, a piston mounted in said cylinder, connections between said piston and the movable portion of said guide member and an automatic 15 tripping mechanism whereby pressure is admitted to said cylinder and the movable guide member pulled away from the stationary member at predetermined times and out of the path of a bar passing between the 20 25 roll stands.
8. In combination with a pair of roll stands, of a normally closed guide member extending from one stand to the other, support members for said guide member, the 30 said guide member being composed of a normally stationary member and a movable member having a guide slot therethrough, a cylinder, a piston in said cylinder, means for admitting pressure to the rear of said cylinder, and automatic means for admitting an 35 exhausting pressure from the forward end of said cylinder by the passing of a strip of material through said guide member and out of the path of the strip of material passing 40 through the said guide member.
9. In combination with a pair of roll stands, of a normally closed guide member extending from one stand to the other, support members for said guide member, the 45 said guide member being composed of a normally stationary member and a movable member having a guide slot therethrough, a cylinder, a piston in said cylinder, means for admitting pressure to the rear of said 50 cylinder, automatic means for admitting an exhausting pressure from the forward end of said cylinder by the passing of a strip of material through said guide member, and means for limiting the travel of said piston.
- 55 10. In combination with a pair of roll stands, a bodily adjustable guide member positioned therebetween comprising a normally stationary member and a movable member having a channel therein positioned in side 60 to side contact with said stationary member when said channel is in closed position, supporting shafts at each end of said guide member upon which the said guide member is slidably mounted and means whereby the 65 said movable member is moved toward and away from the said stationary member, thereby closing and opening the said channel.
11. In combination with a pair of roll stands, a bodily adjustable guide member 70 positioned therebetween comprising a normally stationary member and a movable member having an open-sided channel therein positioned in side to side contact with said stationary member when said channel is in closed position, supporting shafts mounted upon the roll stands upon which the said guide member is guidedly mounted, a cylinder, a piston in said cylinder, and connections between said piston and said 75 movable portion of said guide member, means for admitting a fluid pressure at the rear of said piston adapted to bring the portions of said guide member in side to side contact with each other, a fluid pressure supply line to the forward end of said cylinder, and an automatically operated valve controlling the admission of a pressure fluid to the forward end of said cylinder and exhausting pressure therefrom. 80 85 90
12. In combination with a pair of roll stands, a bodily adjustable guide member positioned therebetween comprising a normally stationary member and a movable member having an open-sided channel therein positioned in side to side contact with said stationary member when said channel is in closed position, supporting shafts mounted upon the roll stands upon which the said guide member is guidedly mounted, a cylinder, a piston in said cylinder and connections between said piston and said movable portion of said guide member, means for admitting a fluid pressure at the rear of said piston adapted to bring the portions of said 95 100 105 guide member in side to side contact with each other, a valve held in normally closed position when said guide member is open and means whereby the said valve is automatically closed when a strip of material reaches a predetermined position in the said guide. 110
13. In combination with a pair of roll stands, a bodily adjustable guide member positioned therebetween, comprising a normally stationary member and a movable member having an open-sided channel therein positioned in side to side contact with said stationary member when said channel is in closed position, supporting shafts mounted upon the roll stands upon which the said guide member is guidedly mounted, a cylinder, a piston in said cylinder, and connections between said piston and said movable portion of said guide member, means for admitting a fluid pressure at the rear of said piston adapted to bring the portions of said guide member in side to side contact with each other, a fluid pressure supply line to the forward end of said cylinder, a valve 115 120 125 130

- held in normally closed position when said guide channel is open, a disk secured to said valve for operating the same, a spring secured to said disc adapted to normally close the said valve, a trip connected to said channel operated by a strip of material passing therethrough and a catch secured by the forward end of said piston adapted to turn said valve into closed position by the backward travel of the said piston.
14. In combination with a pair of roll stands, a pair of longitudinally extending U-shaped members in side to side relation with each other, supporting means at each end of the said members, and means whereby the said members are moved into engagement with each other forming a closed guiding channel and a reversal of operation of

the said means moving the members out of engagement with each other and opening the 20 said channel.

15. In combination with a pair of roll stands, a guide member having an open sided channel therein, a second guide member normally held in stationary position 25 alongside of the first mentioned guide member, support members positioned at each end of the said guide member, and means operated by the passing of a bar through the said guide member whereby the guide member having the channel therein is pulled out of the path of a bar of metal passing between the roll stands.

Signed at Gary, Indiana, this third day of August, 1923.

RANDOLPH B. HANCOCK.
